UNITED STATES PATENT OFFICE.

GARNET W. MCKEE, OF ROCKFORD, ILLINOIS.

FUEL MIXER.

Application filed May 23, 1922. Serial No. 563,059.

This invention relates to fuel mixers, and more particularly to mixers for supplying air and gas in the proper proportions for industrial purposes, such as the heating of 5 furnaces of various kinds and other apparatus which utilizes gas for fuel.

One of the primary purposes of my present invention is to provide a mixer which will deliver for all conditions of use, ranging 10 from the maximum capacity of the burners to the minimum turn down requirements, a mixture comprising the proper proportions of air and gas.

Another object is to provide a mixer which 15 will deliver at all times a highly energized mixture i. e., a mixture not only of the proper proportions, but also under the requisite pressure to result in high efficiency at the burners and minimize the liability of 20 flare backs.

Still another and highly important object 25 of my invention is the provision of a mixer possessing the advantages above mentioned, which can be operated from a single control. In other words, the manipulation of a single 30 control lever serves to regulate the heat delivered by the burners, and since this control regulates the quantity only of the mixture delivered, any liability of delivering an inefficient mixture, either too rich or too lean, such as is apt to occur with devices in which the air and gas supplies are independently controlled, is obviated.

A further purpose of my prevent invention, therefore, is to provide an apparatus 35 which will deliver, at all times in operation, a predetermined quantity of air under relatively high pressure, and a sufficient predetermined quantity of gas, to produce a mixture 40 of the requisite quantity and proportions for turn down purposes. This mixture is supplemented when additional fuel is required, by opening the control valve which adds to this initial mixture, any desired 45 quantity of air and gas always in predetermined proportions, so that the resultant mixture delivered to the burners is always of the requisite proportions.

Another object of the invention is to provide 50 for regulation to a fine degree of nicety of the relative proportions of air and gas, both in the initial and in the supplemental mixtures, so that the most efficient mixture can be secured with the many and various 55 grades and characters of gas employed for industrial purposes.

Another feature of my invention resides in the fact that, after the apparatus has been set and adjusted for any particular grade of gas, it may be operated to deliver the mixture 60 in any desired quantities by the manipulation of a single control lever, and without varying the proportion of the mixture. Furthermore, should it be found that at some point in the turn down, the proportion 65 of gas in the mixture is a little too high or a little too low, such error may be rectified by a further adjustment provided for by my invention.

For the purpose of facilitating an understanding 70 of my invention, I have illustrated on the accompanying drawings a preferred embodiment thereof, from an inspection of which, when considered in connection with the following description, the construction, 75 operation and inherent advantages of my invention should be readily understood and appreciated.

Referring to the drawings: Fig. 1 is a vertical sectional view through 80 a mixer embodying my invention;

Fig. 2 is a fragmentary elevational view looking toward the left at Fig. 1 at the height of the air intake port;

Fig. 3 is a plan view of the mixer shown 85 in Fig. 1; and

Figs. 4 and 5 are vertical and horizontal sectional views, taken on the lines 4—4 and 5—5 respectively, of Fig. 1.

Referring to the drawings, reference character 90 6 indicates a fuel mixture delivery conduit, preferably of substantially Venturi-shape near its receiving end and connected at its delivery end with the burners of the apparatus to which the mixture is delivered. In the form of the invention illustrated, the receiving end of this conduit is threaded into a T-fitting 7, the end of this fitting opposed to the conduit 6 being closed by a plug 8 through which projects an air supply pipe 9 connected to any suitable source of air under the requisite pressure. The delivery end of this pipe is provided with a restricted port 11, through which the air under pressure is discharged as a jet into the conduit 6. 105

To the upper side of this fitting there is connected by a nipple 12, a valve casing 13, provided with an air inlet port 14 opening to atmosphere, and a gas inlet port 15 to which gas is supplied from a pipe 16. In 110 order to ensure a uniform delivery of gas, a pressure regulator or reducing valve (not

shown) is interposed in the pipe 16, so that the gas will always be delivered to the valve casing at a uniform pressure, preferably substantially atmospheric pressure, irrespective of pressure fluctuations in the gas supply line.

Within this casing there is rotatably mounted a proportional mixing valve 17, preferably substantially like that disclosed in my prior Patent No. 1,404,211 issued January 24, 1922. This valve is provided with a port 18 adapted to register with the port 15, and gas entering through this port is deflected downwardly toward the delivery end of the valve casing by a longitudinally disposed partition wall 19. The valve is also provided with an air intake port 21 adapted to register with the port 14, and the valve ports are so disposed in relation to the casing ports that when the valve is turned, both ports will be simultaneously opened or closed, as the case may be, substantially equal amounts to maintain a predetermined proportion between the amounts of air and gas entering the valve casing. To compensate for the difference in shape of the air and gas inlet ports, the port 21 has its lower end formed on a curve, as indicated at 22, Fig. 2, so that as this port approaches closed position, its area is reduced proportional to the reduction in area of the gas port 18. This reduction will be apparent from Fig. 2, wherein the position of the port when in partially closed position is shown in dotted lines.

To provide for the attainment of a desired proportion of air and gas which will be admitted by this valve, the valve is adapted to be vertically adjusted in its casing, and with this end in view, the valve body is provided with an overhanging bracket 23, by which the valve is suspended in its casing upon a bar 24 mounted upon the top of the casing 13, an adjustable set screw 25 being threaded through the bracket 23 into engagement with the bar 24 by which the weight of the valve is carried. A handle 26 is adjustably mounted upon the post 27 extending upwardly from the bracket 23 and a lock nut 28 serves to lock the screw 25 in adjusted position. The handle is also locked by a set screw 29. The adjustment of the handle 26 is provided in order that an index finger 31 projecting radially from the hub of the handle may be disposed in the requisite position over a scale 32 provided upon the top of the valve casing, which assists the operator in determining the extent of opening or closing of the valve by manipulation of the handle lever. When the valve is fully opened a lug 33 projecting downwardly from the lever 26 engages a lug 34 projecting radially from the casing 13 and closing movements of the valve may be regulated by an adjustable abutment screw 35 thread-

ed through a stud 36 projecting radially from the valve casing. The valve may be locked in any desired position by a set screw 37 threaded through the lug 33 and adapted to be clamped against the wall of the casing. 70

It will be apparent that if the screw 25 is manipulated to raise the valve 17, the area of the gas inlet port 18 will be increased, while the area of the air inlet port 21 will be diminished. Consequently, by adjusting 75 the valve to the requisite height, the proper proportions of air and gas will be admitted by the valve when it is open. Due to the shape of the inlet ports, the relative proportions of air and gas will be maintained in 80 any open or partially open position of the valve, and the quantity of mixture may be regulated as desired by swinging the lever 26 in one direction or the other.

In order to provide for further accuracy 85 in securing the requisite proportions of air and gas, delivered by this valve, the valve wall is provided beneath the port 21 with a small port 38 (Fig. 5), and a stud or rib 39 on the casing is provided with a series 90 of ducts 41 adapted to register with the port 38 in different positions of the valve. These ducts may communicate at their outer ends with atmosphere through a slot 42, and any or all of them may be closed by screws 43 95 threaded into the outer ends of the ducts. If, therefore, any grade of gas with which the apparatus may be used requires the admission of more air at any point in the opening or closing movements of the valve, this 100 additional air may be supplied by removing from one or more of the ducts 41, its screw plug 43, and if less than the amount of air which would be admitted through one of these ducts when fully opened is required, 105 the quantity may be regulated to a fine degree of nicety by adjusting its screw plug in the manner of a valve to admit a greater or lesser quantity of air. When gas is admitted through the port 18, just sufficient air 110 is admitted simultaneously through the proportional mixing valve to produce a mixture of the requisite proportions.

Gas in proportion to the amount of air under pressure delivered through the jet orifice 11 is admitted independently of the control valve through a by-pass 44 formed in the wall of the casing 13, and the amount of gas thus by-passed may be regulated by an adjustable regulating screw 45 threaded 115 through the wall of the duct and adapted to cooperate with a plug 46 threaded through the opposite wall. The regulating screw 45 is adjusted so that the gas delivered through this by-pass will enter in just the requisite 120 proportions with respect to the air admitted through the orifice 11 to produce a mixture of the desired proportions. If, therefore, the valve 17 should be fully shut off, there will still be delivered sufficient gas through 125 130

the by-pass 44 and air through the orifice 11 to produce a mixture of the requisite proportions and in sufficient quantities to be discharged through the conduit 6 at sufficient 5 velocity to supply the minimum requirements of the burners without permitting a flare-back.

For illustrative purposes, let us assume that the maximum requirements of the burners are 200 feet of gas per hour which, to produce a proper combustible mixture, should be mixed with approximately 1200 feet of air. The mixing valve 17 will be set to deliver when fully opened, approximately 15 170 feet of gas and 1020 feet of air, while the orifice 11 is adapted to deliver under high pressure 180 feet of air, and the regulating screw 45 is adjusted so that 30 feet 20 of gas will be delivered through the by-pass. When the valve 17 is entirely shut off, a mixture of air and gas from the orifice 11 and the by-pass 44 will be delivered to the conduit 6 in a ratio of six to one, producing a combustible mixture of the proper 25 portions and of the proper quantity for turn-down purposes. When more fuel is required the valve 17 may be opened, admitting the requisite additional amount of air and gas in the proper proportions. Different 30 grades of gas will, of course, necessitate different proportions than those mentioned which are merely illustrative.

It will be apparent from the foregoing that I have provided a mixer, providing two 35 independent sources of air and gas supply, the primary mixture employed for turn-down purposes being composed of high pressure air from the pipe 9 and the requisite amount of gas from the by-pass 44, and the 40 supplemental mixture being furnished in desired amounts by manipulating the valve 17. A mixture of the desired proportions, therefore, will always be furnished for every condition of use, and the device may be operated and regulated from the single control lever since the primary mixture, once the 45 regulating screw 45 has been set, need not be thereafter adjusted. The quantity of mixture, ranging from the minimum turn-down to the maximum capacity of the burners, may 50 be regulated by simply manipulating the handle 26 and the mixture will always be delivered by my device in the proper proportions and under the requisite pressure under all conditions. The details of construction, illustrated and described may 55 obviously be varied within wide limits without departing from the essence of the invention as defined in the following claims.

60 I claim:

1. In a fuel mixer, the combination of a fuel mixture delivery conduit, a manually controlled valve for delivering to said conduit desired quantities of air and gas in predetermined proportions, means for de-

livering air under pressure into said conduit, and means independent from said valve for delivering gas in quantities proportional to the air delivered under pressure. 70

2. In a fuel mixer, the combination of a fuel mixture conduit, means for delivering gas and air in predetermined proportions and in regulatable quantities to said conduit, means for delivering air under relatively 75 high pressure to said conduit, and a bypass through which gas is delivered in predetermined proportions in respect to said high pressure air.

3. In a fuel mixer, the combination of a mixture delivery conduit, a manually controlled proportional mixing valve for delivering air and gas in predetermined proportions to said conduit, and means, including a gas by-pass and a high pressure air 85 delivery device for delivering, a predetermined quantity of air under pressure and gas in predetermined proportions, to said conduit when said valve is closed. 80

4. In a fuel mixer, the combination of a valve casing, a mixture delivery conduit connected therewith, a manually controlled proportional mixing valve in said casing for delivering air and gas to said conduit in predetermined proportions, a by-pass for delivering gas independently of said valve, and a high pressure air pipe adapted to deliver into said conduit. 90

5. A fuel mixer, comprising a rotatable valve provided with air and gas inlet ports, 100 said air inlet port being of diminished dimensions at one side when fully opened means for delivering gas to said gas inlet port; and adjustable means effective at a plurality of positions of said valve for admitting additional air through said valve. 105

6. A fuel mixer, comprising a valve casing having a gas port, an adjustable gas duct, an air port, and a plurality of adjustable air ducts, and a rotatable proportional mixing valve having a gas port registerable with said gas port of said casing and a plurality of air ports registerable with said air port and said air ducts of said casing. 110

7. In a fuel mixer, the combination of a valve casing, a proportional mixing valve mounted therein provided with air and gas inlet ports, a gas by-pass around said valve, means for controlling the effective area of said by-pass, air inlet ducts through said casing wall, means for controlling the effective area of said ducts, and means independent of said air inlet port for supplying air under high pressure. 115

8. In a fuel mixer, the combination of a mixing chamber, a valve casing, means for delivering gas to said casing a proportional mixing valve mounted in said casing and adapted to deliver air and gas in pre- 120

125

determined proportions to said mixing chamber, and adjustable means independent of the valve for delivering a combustible mixture to said chamber.

- 5 9. A fuel mixer, comprising a mixture conduit, means for delivering air under pressure and fuel in predetermined proportions to said conduit to form a combustible turn down mixture delivered at a speed greater
10 than the rate of flame propagation thereof, and means for further delivering to said conduit at will and in regulated quantities supplemental to and for admixture with said turn down mixture a mixture of fuel and
15 air in predetermined proportions suitable for working purposes.

10. The combination with a mixture conduit, of means for delivering to said conduit a combustible mixture of fuel and air, 20 the air being delivered under such pressure that the speed of the mixture formed therefrom is greater than the rate of flame propagation of said mixture, said fuel delivery being induced by said air pressure and 25 manually controlled means for delivering to said conduit in regulated quantities a supplemental mixture of air and fuel in predetermined proportion.

11. A fuel mixer, comprising a casing 30 provided with air and gas inlet ports, a valve rotatably mounted therein and provided with ports adapted to register with the casing ports, said casing being also provided with a plurality of auxiliary air inlet ducts and the valve being provided with an auxiliary port adapted to register successively with said ducts upon rotative movement of the valve, and means whereby desired ones of said ducts may be closed 35 40 whereby to regulate the supply of auxiliary air.

12. In a fuel mixer, in combination, a

fuel mixture conduit, means for delivering a primary combustible mixture to said conduit consisting of a comparatively high 45 pressure delivery of air and an induced delivery of gas, and a proportional mixing valve for delivering to said conduit supplemental to and for admixture with said primary mixture, air and gas in predetermined 50 proportions suitable for working purposes, the delivery of said primary air and gas being continuous and serving after the mixing valve is closed as a turn down mixture the speed of which is greater than the 55 rate of flame propagation thereof.

13. In a fuel mixer, in combination, a fuel mixture delivery conduit, means for continuously delivering air and gas in predetermined proportions to said conduit to 60 form a combustible turn down mixture delivered at a speed greater than the rate of flame propagation thereof, and a manually controlled proportional mixing valve for delivering to said conduit supplemental to 65 and for admixture with said turn down mixture, air and gas in predetermined proportions suitable for working purposes.

14. In combination, a source of gas supply, a fuel delivery conduit, means for delivering high pressure air into said conduit, a proportional mixing valve connecting said gas supply and conduit and having a valve operable for delivering gas and air in predetermined proportions to said conduit, and 75 a by-pass between said gas supply and conduit whereby when said valve is closed gas will be delivered to said conduit in such proportion of said high pressure air as to form a combustible turn down mixture the delivery of which is at a speed greater than 80 the rate of flame propagation thereof.

GARNET W. MCKEE.
